CLAIM

The ornamental design for a combined jug, stirrer, and ice holder, as shown and described.

DESCRIPTION

FIG. 1 is a side elevational view of a combined jug, stirrer, and ice holder showing my new design, the side opposite being a mirror image thereof;

FIG. 2 is an elevational view from the left of FIG. 1; FIG. 3 is an enlarged sectional view taken on line 3—3 of FIG. 2;

FIG. 4 is a top plan view; and

FIG. 5 is a bottom plan view thereof.

FIG. 1FIG. 5*FIG. 2*FIG. 4FIG. 3*
